Inventor:
I Irving Kulik

UNITED STATES PATENT OFFICE

IRVING KULIK, OF BROOKLYN, NEW YORK

ABSORBENT ROLL

Application filed June 18, 1927. Serial No. 199,780.

The present invention relates to absorbent material of cotton, cellulose, paper, or cloth, and my invention can be used where shape maintaining qualities are desired for these 5 materials.

The absorbent roll which constitutes the present invention is of the type which is employed by dentists to draw off saliva and moisture buccally and lingually about teeth 10 and in general prevent saliva from reaching the area operated upon in the patient's mouth.

In the drawings:

Fig. 1 is a cross section showing that there 15 is a hollow in the absorbent roll for reception of a flexible strip of material, said flexible strip when inserted thus being surrounded by absorbent material as shown in other views.

Fig. 2 is a view similar to Fig. 1, showing the referred to strip of material in 20 position.

Fig. 3 shows the flexible material instead 25 of being solid as in Fig. 2, is tubular and has perforations along its walls.

Fig. 4 is a cross section of my absorbent 30 roll showing a hollow containing a tubular flexible material with perforations and said tubular flexible material containing a solid length of flexible material.

Fig. 5 is a cross section showing a hollow 35 in the absorbent roll containing sections of the flexible material referred to.

Fig. 6 is a cross section showing a hollow 40 in the absorbent roll containing a tubular flexible material with perforations and said tubular flexible material containing sections of flexible material.

Fig. 7 is a side elevation showing the invention applied to absorbent rolls containing sections of flexible material, as shown 45 in Figures 5 and 6 with lines appearing on the surface to show where the absorbent rolls can be cut or torn and where the junctions of the sections of flexible material are, the tearing or cutting is easiest.

Fig. 8 is a side elevation showing the invention with a portion of the absorbent roll 50 removed.

Fig. 9 shows a practical application of my invention.

Fig. 10 shows another practical application of my invention.

Fig. 11 shows still another practical application of my invention.

Fig. 12 shows a cross section of a saliva ejector that can be used in connection with my absorbent roll.

The absorbent roll body A—A, Fig. 1, 60 has running through it a hollow which encloses a flexible material in the nature of a wire C Fig. 2.

Instead of a wire a flexible tube D, Fig. 3, can run through the absorbent roll. The 65 flexible tube D, Fig. 3, can contain perforations E.

If it is desired the tubing D, Fig. 4, can contain a flexible wire C, Fig. 4.

Instead of a continuous piece of flexible 70 material like Fig. 2 the absorbent roll can embody sections of flexible material like G, Fig. 5.

The sections of flexible material in the absorbent roll can be enclosed by a flexible 75 tubular material like d in Fig. 6.

The lines H, Fig. 7, can serve to show where the absorbent roll can be conveniently cut or torn apart.

My absorbent roll can be used by the dentist in a wide variety of ways. The dentist can bend my flexible absorbent roll into a shape shown in Fig. 9—the flexible material embodied by the absorbent roll as shown in Figures 1-8, maintaining the absorbent roll in the desired position and shape. With the absorbent roll thus bent out the dentist proceeds to place it in the mouth with the looped portion I, Fig. 9, overlying the cusps or incisal edges of the teeth. The dentist does not have to employ clamps to hold the roll in position as is necessary with the present use of absorbent rolls.

With my flexible absorbent roll, shaping 95 it as shown in Fig. 9, and placing it in the mouth, with the horizontal portion J or K held in place by the pressure of the lips or cheeks against the absorbent roll towards the alveolar ridge, the lingual 100

prong of the roll will thus be kept in position.

Let us assume that the dentist wants to use my absorbent roll on the lower posterior right side of the mouth. He bends up a straight absorbent roll having any of my flexible structures Figures 1-8, into the shape Fig. 9. He pushes the prong J, Fig. 9, down between and alongside the teeth and cheeks, which brings the loop I, Fig. 9, over the occlusal surfaces of the teeth, and brings simultaneously the prong K, Fig. 9, alongside the lingual surfaces of the teeth and gums. The pressure of the cheeks will hold the whole cotton roll in position.

For work upon the upper posterior teeth my absorbent roll is bent in the same way, used in the same way, and has the same highly advantageous properties.

Let us assume that the dentist wants to use my absorbent roll for work on the anterior teeth. He bends up a straight absorbent roll having any of the structures Figures 1-8 into the shape, Fig. 9. He pushes the prong K, Fig. 9, between and alongside the teeth and lips, which brings the loop I, Fig. 9, over the incisal edges of the teeth, and brings simultaneously the prong J, Fig. 9, alongside the lingual surface of the teeth and gums. The pressure of the lips will hold the whole absorbent roll in position.

There are quite many advantages derived from an absorbent roll of my invention. The slipping about of absorbent rolls in the mouth is a fact well known amongst dentists and is very frequently a source of serious trouble and consternation during a dental operative procedure. Very often an absorbent roll will slip unnoticed near a surface of a tooth where a crown or inlay is being cemented and have some of its absorbent material caught beneath the cemented crown or inlay, becoming permanently fastened there with the setting of the cement to the detriment of the patient and to the exasperation of the dentist. It is understood that the fit of the best fitting crown or inlay is ruined by the shreds of absorbent material thus caught, after the remainder of the absorbent roll is torn away.

Wherever it is possible the dentist uses clamps to hold the absorbent rolls in place. But he cannot use a clamp where it is required to have the patient close the mouth from time to time during the course of an operation, viz., examining for articulation in the process of a restorative operation. To this my absorbent roll of flexible form is considerably of advantage. The dentist can bend my absorbent roll to the shape Fig. 9 and with the loop I, Fig. 9, passing over an appropriate space of a missing tooth or passing over the space posteriorly of the last molar the patient is able to close the mouth

and if anything happens, instead of pushing the absorbent roll into a filling or capping area, as would ordinarily happen with the closing of the mouth, my absorbent roll is pushed away from the filling or capping area. The value of such a feature will be highly appreciated by a dentist.

Dentists often resort to powdering with certain powder ordinary absorbent rolls to avoid its slipping about the area in which it is placed. But this staying effect of the powder is very quickly lost by the slippery mucous saliva coming in contact with the absorbent roll.

To prevent absorbent rolls from slipping dentists are compelled wherever possible to use a series of clamps, known as cotton roll clamps, and a number of each kind have to be kept on hand, such as molar clamps, bicuspid and anterior clamps. These clamps which have to be adjusted on the teeth by forceps, but are not very easily adjustable in most cases, and far from comfortable to the patient, very often slipping down the tooth into the patient's gum with consequent excruciating pain. Clamps will often slip by themselves on the smooth tooth surface into the patient's gum, whereupon, the dentist must instantly stop his work, which work as every body knows a patient wants to be quickly through, and after reassuring the patient that the clamp will not slip any more, being that it was adjusted, only to find that the clamp soon slips again.

The clamps referred to are powerful spring-like affairs having a shape like the Fig. 9 of the appended drawing. The material comprising the clamp is of such powerful springlike material and construction that it can only be manipulated with stout forceps. This powerful spring effect is employed together with a knife edged termination of the clamp in order to grip the smooth surface of the tooth. It is practical to assume that the knifed edged grasping parts of the clamp, under the powerful pressure of the clamp, scratches and otherwise harms the enamel of the tooth.

The evils of clamp use have always been known amongst dentists and numerous devices are marketed to obviate the use of clamps with absorbent rolls when work on the lower jaw is performed—for the upper jaw nothing but clamps being possible to use with present forms of absorbent rolls. These devices are practically all alike in that they hold the absorbent roll in position like one does by placing his index and middle finger over the cotton rolls and the thumb of the same hand below the patient's jaw or beneath the patient's chin. These devices, however, are very bulky and often interfere with the work of a dentist. Furthermore, these devices cannot be used, as stated, for work on the upper jaw. Conse-

quently the upper jaw is limited to the use of clamps with the attending evils.

Although limited for the most part to clamps for holding absorbent rolls in position, as explained, the dentist very often finds that he cannot use even this unsatisfactory means of holding absorbent rolls. The tooth may be too short, causing the clamp through its spring action, to jump off the tooth. Or the tooth may be peg shaped and the clasp won't hold, also jumping in the manner explained. Such absorbent rolls as mine, which keep themselves in position, serve in such cases very usefully. Thus with my absorbent roll requiring no clamps or other retaining means the difficulties described are all overcome to the gratification of the patient and the dentist.

20 The loop I, Fig. 9, of the absorbent roll gives a greater amount of absorbent material than when buccal and lingual pieces of absorbent material are used. Consequently a longer absorption period is obtained.

25 The flexibility of the absorbent roll gives rise to other desirable features besides those alluded to. My absorbent roll can be doubled up, as shown in Fig. 10, to the right 30 of the line QQ, which is advantageous in several ways. First, where it is desired to keep the absorbent roll in firmer position, by doubling the absorbent roll where it abuts the cheeks or lips adds thickness with consequently greater crowding and staying effect 35 to the part of the absorbent roll within its confining space, between the cheeks or lips and the gums, thus, keeping the facial as well as the lingual portions of my absorbent 40 roll firmly fixed in position. Secondly, doubling my absorbent roll naturally means more absorptive material and a longer absorption period for the absorbent roll.

45 While the doubling of my absorbent roll is a comparatively simple thing because of its flexible properties, it is an impossible thing to do with ordinary absorbent rolls. Furthermore, with my absorbent roll the doubling can be done in any direction. Of 50 course, my absorbent roll can be tripled as well as doubled.

Some dentists prefer to tear their absorbent rolls with the fingers instead of cutting it with a scissors. For this reason I show 55 my flexible material also in sectioned off form, viz, Figures 4, 5, and 6. And with the lines H, Fig. 7, exteriorly of the absorbent roll to show about where the sections terminate. It is a simple matter to tear the 60 absorbent roll by hand—the sectioned off pieces of flexible material permitting it. Where tubular material is employed, like Figures 3, 4, and 6, said tubular material can be of easily tearable material or substance. Thus a small piece of absorbent 65

material, Fig. 8, can be torn away or cut away from a regular sized strip of absorbent material.

My absorbent roll can be used with a saliva ejector in a novel way. A saliva 70 ejector like Fig. 12 can be pushed into the hollow of the absorbent roll, presenting an appearance Fig. 11, to draw off saliva absorbed by my novel absorbent roll. Such a saliva ejector will work especially well when 75 my absorbent roll is provided with a tubular structure like Figures 3, 4, and 6 and the tapered end of the saliva ejector 12 is pushed into the tubular structure D.

The flexible material need not be perfectly straight but can partake of irregularities 80 of any nature.

Having described my invention what I claim as new and wish to secure by Letters Patent is:

1. A dental absorbent roll hollowed out 85 interiorly and inside of which hollow is a flexible hollowed out member.

2. An article of manufacture consisting of a dental absorbent roll and said absorbent 90 roll embodying a flexible wire.

3. An article of manufacture consisting of a dental absorbent roll and said absorbent roll embodying a flexible wire to render 95 said absorbent roll shape retaining when bent.

4. An article of manufacture consisting of a dental absorbent roll and said absorbent roll embodying a flexible wire to render 100 said absorbent roll partially rigid so as to maintain an angular shape when bent.

5. An article of manufacture consisting of a dental absorbent roll and said absorbent roll being hollowed out interiorly and inside of which hollow is another hollowed 105 out part.
